3 Sheets-Sheet 3

UNITED STATES PATENT OFFICE.

JAMES P. BEATTY, OF DETROIT, MICHIGAN, ASSIGNOR TO THE ELECTROGRAPH COMPANY, OF DETROIT, MICHIGAN, A CORPORATION OF MICHIGAN.

PRINTING PRESS.

Application filed October 29, 1925. Serial No. 65,534.

My invention relates to printing presses, preferably the type known as a "Gordon press", and the method of using the same, and an object of my improvements is to provide a method and improved apparatus that shall print upon both sides of a sheet in one operation of the press.

I secure this object in the apparatus illustrated in the accompanying drawings in which—

Figure 1, is a side view of a printing press of usual construction and embodying my invention therein and illustrating its operation.

15 Figure 2, is a front elevation of a portion of the bed with the form thereon.

Figure 3, is a section on the line 3—3—3—3 of Figure 2, the press being in its closed position.

20 Figure 4, is a perspective view showing the platen, a portion of the bed with the form thereon, and a frame, partly broken away, carrying an inking ribbon and the frisket sheets.

25 Figure 5, is a view similar to Figure 4 taken from a different position.

Figure 6, is a face view of the card printed upon the press.

30 *a*, is the platen, and *b*, is the bed. *c*, is a frame interposed between the platen *a* and bed *b* and adapted to carry an inking ribbon *c*². *c*³ and *c*⁴ are two frisket sheets carried by the frame *c* between which sheets travel the inking ribbon *c*². *d*, is an address plate resting upon the platen *a* and positioned by stops *ad*. A plate *d* bearing the address is inserted in position shown in Figure 4 after each operation of the press.

35 *e*, is a block or platen fixed in the form on the bed *b* in such a position that it shall come opposite the plate *d* when the impression is taken. *c*^{3a}, is an opening formed through the frisket sheet *c*³ to permit the letters of the plate *d* to pass and *c*^{4a} indicates a similar opening in the frisket sheets *c*⁴.

40 *f*, indicates the type adapted to print the message. *g*, is a card held upon the frisket sheet *c*⁴ by positioning stops *cg* which card constitutes the sheet to be printed upon and is supported by the frisket sheet and said stops.

45 The parts being in the position described, the press is operated bringing the platen *a*

and the form upon the bed *b* into position to form the impress. The type *f* prints 55 the message upon one portion of one side of the card *g* and the type on the address plate *d* acting through the apertures *c*^{3a} and *c*^{4a} print the address through the inking ribbon *c*² upon a portion of the other side of 60 the card that is not opposite the first mentioned portion. The block or platen *e* forms a surface against which the card *g* is pressed when the address is being printed upon it. In Figure 6, the position of the 65 address *g*³ upon the card is indicated in broken lines and the message being on the side of the card toward the observer, is shown in full lines in *g*². The printed card is removed and a blank card *g* is placed in 70 position after each operation of the press.

What I claim is:—

1. In a printing press, two opposed surfaces, each bearing type adapted to print upon a sheet, and each bearing a platen surface, type forms and platen surfaces being opposed to each other, a frisket adapted to support the sheet to be printed on between said surfaces with opposite surfaces of the sheet exposed to said type, and means for 75 supporting said sheet upon said frisket as described.

2. In a printing press, two opposed surfaces, each bearing type adapted to print upon a sheet, and each bearing a platen 80 surface, type forms and platen surfaces being opposed to each other, a frisket, having an opening therein adapted to permit the action of the type, interposed between said surfaces, an inking ribbon, means for supporting said ribbon adjacent to said frisket as described.

3. In a printing press, two opposed surfaces, each bearing type adapted to print upon a sheet, and each bearing a platen 85 surface, type forms and platen surfaces being opposed to each other, a frisket, having an opening therein adapted to permit the action of the type, interposed between said surfaces, an inking ribbon, means for supporting said ribbon adjacent to said frisket as described.

4. In a printing press, two opposed surfaces, each bearing type adapted to print upon a sheet, and each bearing a platen 100 surface, type forms and platen surfaces being opposed to each other, a double frisket sheet having an opening therein adapted to permit the action of the type interposed be-

2
tween said surfaces, an inking ribbon, means for supporting said ribbon between said frisket-sheet opposite said opening, inking rollers adapted to ink the type on one of said surfaces, and a support upon the outer surface of the frisket nearest the inking rollers, adapted to hold a sheet over said

opening while being printed upon, the type on the other of said surfaces being adapted to act through said opening and said ribbon. 10
In testimony whereof, I sign this specification.

JAMES P. BEATTY.
